ATTORNEY

UNITED STATES PATENT OFFICE

2,514,040

HOPPER DISCHARGE CONTROL FOR
RAILWAY CARSCarolus L. Eksergian, Media, Pa., assignor to The
Budd Company, Philadelphia, Pa., a corpora-
tion of Pennsylvania

Application November 3, 1947, Serial No. 783,804

5 Claims. (Cl. 4-8)

1

The invention relates to a hopper discharge control for moving vehicles and, more particularly, to such a control as applied to railway vehicles.

In hoppers provided on railway cars, it is desirable to have them available for use at all times, even when the car is stopped in a station or moving slowly into and out of the station. It is, however, not desirable to have the discharge from the hopper upon the roadbed at such times as the car is standing still or moving slowly into or out of a station. Such discharge is usually through a generally tubular chute extending downwardly from the hopper well below the floor of the car and if the chute extends downwardly below the top of the truck where it is likely to be struck by the swivelling of the truck, its lower portion is made flexible to avoid fouling the truck.

The upper portion of the tubular chute may be utilized as a chamber for holding the hopper discharge, if the hopper is used while the car is standing still or moving slowly, while the lower discharge end is held closed under these conditions by a suitable valve under the control of the speed of travel of the car.

It is the object of my invention to provide a valve for this purpose which is simple in form and efficient in operation and well adapted for use in a flexible chute of the class above referred to. Such valve preferably consists of an inflatable bag or ball, which is adapted to be inflated or expanded to engage the sides of the chute and close it, or to be deflated or collapsed to hold the chute open. Means are provided controlled by the speed of travel of the car to maintain the valve deflated when the car is travelling above a predetermined rate and to cause it to be inflated when the car is travelling below said rate, say 5 miles per hour, or standing still.

This object and other and further objects and advantages will become clear from the following detailed description when read in connection with the drawings forming a part of this specification.

In the drawing:

Figure 1 shows more or less diagrammatically the invention as applied to a railway car; and

Figure 2 is a detail sectional view through the discharge chute and the valve therein.

In the drawing, the floor of the car is represented by the numeral 10. 11 represents a wheel and axle assembly of one of the trucks supporting the car on the rails, indicated at 12.

A hopper is generally indicated at 13 seated on the floor of the car and extended downwardly below the floor of the car by a generally tubular

2

chute 14. In the form shown, the upper portion 15 of this chute is rigid and the lower portion 16 is flexible to allow it to bend away if it happens to be in a position where it may be struck by the swivelling truck. The discharge chute is normally closed from the bowl portion 17 of the hopper by a flap valve 18, shown in full lines in open position and in dot-and-dash lines in closed position. This flap valve 18 is operated by the usual foot lever 19 which also operates simultaneously, through the lever-linkage 20 shown in dotted lines, the usual flushing valve 21. With this arrangement, it will be seen that the hopper bowl can be discharged and flushed at all times.

To prevent the discharge from striking the roadbed under certain conditions, is the main purpose of the invention. To allow a substantial chamber to be formed below the flap valve 18 to receive the discharge when the discharge chute 14 is closed, the closing valve 22 is preferably arranged near the lower end of the chute, i. e., in the flexible portion 16 thereof. This valve may comprise a rubber or rubber-like bag or ball which, when inflated, has its walls expanded against the walls of the flexible chute to tightly close it and prevent discharge from its lower end. When deflated, the bag hangs in collapsed condition (as shown in dotted lines) at one side of the chute and offers no material resistance to the free discharge of matter from its lower end.

In the drawings, one form of means has been shown for automatically controlling the inflation and deflation of the valve 22 but it will be understood that this is merely illustrative and that other suitable means could be utilized in place thereof.

According to this form, the bag 22 is connected through a flexible tube 23 passing through a hole in the side of the flexible chute portion to a port 24 in a valve chamber 25. This valve chamber may be carried by the underside of the car, as shown, and is provided with an inlet port 25' and an exhaust port 26, a sliding valve 27 connecting the port 24 with either the inlet port 25' or the exhaust port 26. The valve is normally urged by a spring, as 28, to the position in which the valve bag 22 is connected to the exhaust port, in which position the bag is collapsed, leaving the discharge chute unobstructed.

As shown, the valve is in left-hand position in which it is held against the action of the spring 28 by the solenoid 29 whose core 30 is connected to the valve. In this position, the valve connects the ports 24 and 25', and air under pressure passes from the storage reservoir 31 and pipe 32, through

the valve casing and flexible tube 23 into the bag valve 22 to inflate it, as shown in full lines, and thereby close the lower end of the discharge chute. To avoid excessive pressure, such as might over-expand and tear the bag 22, a reducing valve 33 is preferably provided in the pipe 32.

The means for automatically operating the valve 22 in accordance with the speed of the car may comprise a relay circuit 34 connected with the solenoid 29 and containing a closing switch 35 and a battery 36. The closing switch of this relay circuit is normally held open by a solenoid 37 connected across the lines 38 of a generator 39. This generator may be the usual generator carried by the car body and driven through a belt 40 from the wheel and axle assembly 11 and providing the current for lighting, etc., in the car. With such a generator driven by the car axle, it will be seen that the current output drops with decrease in speed and the solenoid controlled by it may be so adjusted that it allows the closing valve 35 of the relay circuit 34 to close by gravity or otherwise, say at and below a predetermined speed, say 5 miles per hour. As shown, the speed having dropped below this predetermined speed, the relay circuit has been closed and the valve 27 has been shifted to cause the inflation of the chute-closing valve 22. If the hopper is now flushed, the matter is not discharged through the lower end of the chute and it is only after the car has again picked up speed and the closing switch 35 of the relay circuit has been raised to open this circuit that the bag valve 22, being connected to the exhaust port 26, is collapsed and the discharge from the chute can again take place. This collapse may be effected by the natural resilience of the material of the bag or by suitable resilient means associated therewith.

As shown clearly in the detail view of Figure 2, where the bag valve 22 is shown in full lines in the collapsed condition and in dotted lines in the inflated condition, such collapsing means may comprise a coil spring 41 encased in a housing 42 secured to the outer wall of the chute portion 16 vertically at the location of the valve 22 therein. A perforated neck 43 of the bag valve is clamped to an opening 44 in the chute in line with an opening 45 in the inner end of the casing 42. A rod 46 suitably secured at one end to the side of the bag remote from the opening 46, passes through the aligned openings 44 and 45 and the coil spring 41, and has a head 47 on its outer end against which the outer end of the spring bears. The inner end of the spring reacts against the inner end of the housing 42. The spring 41 is just strong enough to collapse the bag, when the tube 23 is connected to the exhaust port 26 of valve chamber 25, and is readily compressed by the air pressure when it is admitted to inflate the bag.

While a specific embodiment of the invention has been herein described in detail, it will be understood that changes and modifications may be made by those skilled in the art without departing from the main features of the invention, and such changes and modifications are intended to be covered by the appended claims.

What is claimed is:

1. A hopper discharge control for railway vehicles comprising in combination, a hopper disposed on the floor of a railway car, a discharge chute of generally tubular form extending downwardly from said hopper a substantial distance

below the car floor, and means for automatically controlling the discharge from the lower end of said chute comprising a normally collapsed but inflatable valve member disposed in said chute and means controlled by the speed of the car for inflating said valve member to close the chute whenever the car speed is less than a predetermined value.

2. A hopper discharge control for railway vehicles comprising in combination, a hopper disposed on the floor of a railway car, a discharge chute of generally tubular form extending downwardly from said hopper a substantial distance below the car floor, and means for automatically controlling the discharge from the lower end of said chute comprising an inflatable valve member disposed in said chute and means controlled by the speed of the car to permit the valve member to remain deflated to permit discharge from the chute when the car is travelling above a predetermined speed and for causing the valve to be inflated to close the chute when the car is travelling below said predetermined speed.

3. A hopper discharge control for railway vehicles comprising in combination, a hopper disposed on the floor of a railway car, a discharge chute of generally tubular form extending downwardly from said hopper a substantial distance below the car floor, at least the lower portion of said chute being flexible, and means for controlling the discharge from the lower end of said chute comprising a collapsible and inflatable valve member disposed in the flexible portion of said chute and means controlled by the speed of the car for effecting the collapse or inflation of said valve member.

4. A hopper discharge control for railway vehicles comprising in combination, a hopper disposed on the floor of a railway car, a discharge chute of generally tubular form extending downwardly from said hopper a substantial distance below the car floor, and means for automatically controlling the discharge from the lower end of said chute comprising an inflatable bag valve member disposed in said chute and means connected therewith and controlled by the train speed to permit collapse of said valve member to open the chute above a predetermined speed and cause inflation of said valve member to close the chute below said predetermined speed.

5. A hopper discharge control for railway vehicles comprising in combination, a hopper disposed on the floor of the car, a discharge chute of generally tubular form extending downwardly from said hopper a substantial distance below the car floor, at least the lower portion of said chute being flexible, and means for controlling the discharge from the lower end of said chute comprising a collapsible and extensible valve member disposed in the flexible portion of said chute and means for extending said valve member to close the chute.
